UNITED STATES PATENT OFFICE

168,251

AUTOMOTIVE HEATER HOUSING

Adolph G. Bergstrom, Rockford, Ill., assignor to
Bergstrom Manufacturing Co., Rockford, Ill.,
a corporation of Illinois

Application April 14, 1951, Serial No. 14,841

Term of patent 7 years

(Cl. D14—6)

To all whom it may concern:

Be it known that I, Adolph G. Bergstrom, a citizen of the United States, residing at Rockford, in the county of Winnebago, and State of Illinois, have invented a new, original and ornamental Design for an Automotive Heater Housing, of which the following is a specification, reference being had to the accompanying drawing forming part thereof.

In the drawings:

Figure 1 is a top plan view of an automotive heater housing embodying my new design,

Fig. 2 is a front elevational view thereof,

Fig. 3 is a side elevational view thereof, and

Fig. 4 is an elevational view of the side opposite Fig. 3, the back of the casing being open and plane.

The dominant features of my design reside in those portions shown by means of full lines in the drawing.

I claim:

The ornamental design for an automotive heater housing, substantially as shown and described.

ADOLPH G. BERGSTROM.
